No. 740,374.

PATENTED SEPT. 29, 1903.

H. J. SHALLER.
VENDING MACHINE.
APPLICATION FILED AUG. 1, 1901.

NO MODEL.

UNITED STATES PATENT OFFICE.

HARRY J. SHALLER, OF ST. LOUIS, MISSOURI.

VENDING-MACHINE.

SPECIFICATION forming part of Letters Patent No. 740,374, dated September 29, 1903.

Application filed August 1, 1901. Serial No. 70,480. (No model.)

To all whom it may concern:

Be it known that I, HARRY J. SHALLER, a citizen of the United States, residing at No. 622 Locust street, St. Louis, Missouri, have invented a certain new and useful Improvement in Vending-Machines, of which the following is a full, clear, and exact description, such as will enable others skilled in the art to which it appertains to make and use the same, reference being had to the accompanying drawings, forming part of this specification, in which—

Figure 1 is a perspective view of the present apparatus. Fig. 2 is an end elevation of the same with the end wall of the casing removed and the lid cut on the line 2 2 of Fig. 5, the parts being illustrated in their normal locking positions and the apparatus being indicated as attached to a support. Fig. 3 is a view generally similar to Fig. 2, but illustrating the parts in their unlocking positions. Fig. 4 is a vertical sectional elevation looking from the front of the apparatus, the left-hand compartment shown in said figure having the section taken on the line X X of Fig. 2 and the right-hand compartment having the section taken on the line Z Z of Fig. 2. Fig. 5 is a top plan view, partly in section, the greater portion of one of the lids being broken away and a portion of the package shown in the compartment provided with said broken lid being broken away. Fig. 6 is an end elevation, partly in section, illustrating the manner of relocking the lid of a compartment and of releasing the coin-retaining operating-lever. Fig. 7 is an elevation of the operating-lever, showing the side opposite to that shown in Figs. 2 and 3. Fig. 8 is a top plan view of the gravity locking-dog for controlling the lid-latch, and Fig. 9 is a view of the tool used for certain purposes in connection with the apparatus.

This invention relates to vending apparatus, and more particularly to such apparatus designed to be attached to the backs of theater-chairs and the like and to be operated through the medium of a deposited coin.

My object is to provide a neat apparatus of the nature indicated simple in construction and efficient in operation.

To this end and also to improve generally upon devices of the nature of the present my

invention consists in the various matters hereinafter described and claimed.

Referring now more particularly to the drawings, A represents a box-like receptacle which is preferably divided into a series of compartments by means of the partition-walls a, each compartment being closed at its top by a separate lid a', which is preferably held closed against the action of a suitable spring a², whereby when a lid is unlocked it is automatically thrown into open position. Across one side of each compartment parallel with the box ends and a short distance from the respective box end or partition-wall, as the case may be, is a wall-plate a³, between which and the neighboring partition-wall or box end the operating parts lie. Each compartment is designed to hold a package or other article to be vended, such packages being illustrated in Figs. 4 and 5. Each package rests upon an upwardly-acting plate-spring a⁴, secured to the bottom of the compartment, (the bottom of the box-like receptacle A,) and when the package is in stored position with the lid of the compartment closed and locked it compresses said spring and rests in the position illustrated by full lines in Fig. 4. When, however, the lid is opened, the said spring raises the package a sufficient distance above the walls of the compartment to permit it to be grasped by the purchaser.

A catch a⁵ is provided upon each lid, at the forward corner thereof, which when the lid is closed lies over the space containing the operating mechanism, and said catch is here shown as a depending hook which enters the said space. When the lid is closed, this hook is engaged by a nose b upon a latch-lever B, suitably pivoted to the plate a³. An operating-lever C is also pivotally connected to said plate, said lever having an extension or finger-piece c, which projects through the space between the wall and plate, which lie at the sides of the operating members, and through a suitable slot a⁶ in the compartment-lid to a point above said lid, whereby said finger-piece can be engaged and operated by the purchaser. The said operating-lever and the latch-lever lie in different planes, as illustrated in Fig. 4, whereby the rocking of said operating-lever upon its pivot does not bring it into engagement with the latch-lever. As will be

more fully hereinafter described, however, the operating-lever is so constructed that a deposited coin or token X is supported by it at its side and in the plane of the said latch, 5 whereby when, after a coin has been deposited, the said operating-lever is thrown the coin engages the latch, as illustrated in Fig. 3, and throws the same out of engagement with the lid-hook, thus permitting the lid to be thrown 10 open by the before-described spring a².

In order to prevent operation of the latch by merely inserting a wire or the like through the coin-slot a⁷ in the lid, and thereby forcing the latch out of locking position, there is provided a gravity locking-dog D. This dog is 15 here shown as a plate d, pivoted upon the wall-plate a³ to lie at the side of the latch, said plate having a lug d', which when the dog is in lower normal position lies just back 20 of the latch and in its path of movement, as shown in Fig. 2, whereby rocking of said latch on its pivot is prevented. The downward movement of the dog can be limited in any 25 suitable manner, that herein shown being by engagement of the said lug with a shoulder e, formed in the guide-strip E. The said latch-lever B and locking-dog D thus constitute latch members, which coöperate to securely lock the compartment-lid. The plate d of 30 said dog lies in the plane of the operating-lever, and at a suitable point said operating-lever is provided with a cam-shoulder c', which when the lever is thrown forwardly, as illustrated in Fig. 3, engages the said locking-dog 35 and causes its free end to ride upwardly upon the cam, thus carrying the lug d' into a position opposite a notch b', formed in the rear edge of the latch B, whereby unlocking movement of said latch is permitted. The lug d' 40 lies in the path of the shoulder below the notch b', and thus locks said latch in position. In the operation of the parts the latch B and the locking-dog D are substantially simultaneously engaged and operated by the coin and 45 the cam-shoulder, respectively.

Preferably each plate a³ has at its top an angle-strip a⁸, which lies above and protects the latch and its locking-dog, and as said strip abuts against the neighboring partition-wall it also serves to hold the plate a³ properly spaced. The end of the latch B is so placed with relation to the end wall of the coin-slot and the lower end of the guide E that a straight wire or other implement inserted through said slot cannot engage and operate the latch.

The operating-lever C lies flat against the end or partition wall, as the case may be, and has in its lower edge a notch c², which receives a pin a⁹, projecting from the plate a³, the lever being thus pivoted upon said pin, but capable of being withdrawn vertically from the casing when the lid is open. At the rear edge of the lever and that portion of its 65 front edge which lies below the latch B are provided anglestrips or flanges c³, which form a seat for the deposited coin H, the top edge

of the forward flange being preferably beveled downwardly and rearwardly, as at c⁴, to accommodate the coin. These flanges extend 70 to the plate a³, and thus also serve to hold the lever properly spaced. A deposited coin of the proper size (say a five-cent piece) therefore rests upon the forward flange c³ and against the rear flange, and is thus supported 75 upon and movable with the lever. Any coin of smaller diameter than that designed to operate the apparatus will merely fall past the seat for the proper coin, as illustrated in Figs. 2 and 3, this smaller coin being marked Z. 80 In order to prevent such smaller coin from resting upon the bottom of the receptacle in a position in which it might obstruct the backward rocking of the operating-lever, a short rib c⁵ is provided upon the lever, said rib being of the general nature of the forward flange c³, whereby the smaller coin seats upon said rib c⁵ and is confined between flanges c³, and thus carried by the lever in its rocking movement. The operating-lever combines with the plate a³ and the flanges c³ to produce a coin-raceway. For an authorized person to obtain the deposited coin, it is only necessary for him to withdraw the lever from the receptacle, whereby the coin becomes readily 95 accessible. A suitable guide-strip E, secured to the plate a³ and extending from the forward wall of the coin-slot in the cover to a point sufficiently near the operating-lever, serves to guide the coin to its seat. Normally 100 the lever is locked against the above-mentioned withdrawal. To effect this, there is pivoted upon the plate a³ a latch F, whose forward end is weighted, as at f, to cause its nose f' to normally lie in an opening c⁶ in the 105 lower portion of the forward flange c³, the said opening being of sufficient size to permit the necessary rocking of the lever on its pivot notwithstanding its engagement by the nose f'. A stop-pin a¹⁰ upon the plate a³ lies 110 in position to be engaged by the lower edge of the latch F when the same is in its normal locking position, and just below the line in which this lower latch edge normally lies and slightly in the rear of the forward edge of 115 the latch there is provided an elongated slot a¹¹ in the plate a³. The latch can thus be engaged and rocked by a suitable tool inserted through said slot a¹¹, and the operating-lever being thus freed it can be withdrawn from 120 the casing. The tool being then removed, the latch falls against the stop-pin and is in position to again engage the operating-lever upon its reinsertion.

In order to provide for throwing the latches 125 B to relock the lids after the same have been closed, the front wall of the receptacle is provided with a series of openings a¹², each of which lies in line with the lower arm of one of the latch-levers. A suitable tool pushed 130 into one of these openings engages a latch B and throws the same into locking engagement with the lid-hook.

The tool heretofore mentioned is illustrated

in Fig. 9. It is merely a plate H, having one end h of a size to enter the openings a¹² and provided upon its other end with a backwardly-extending hook h'. When the tool is held against a plate a³, with its hook h' in the slot a¹¹, an upward pull upon the tool causes the hook to engage and rock the latch F. Preferably the hook-carrying end of the tool is of such width with relation to the distance between the slots a¹¹ and the front wall of the receptacle that when the tool is laid against the desired plate a³, with its edge against the front wall of the receptacle, and is then slid downwardly the hook is guided into the slot a¹¹.

15 The several compartments of the receptacle being filled and the lids being closed and locked, the purchaser deposits his coin through the coin-slot in one of the lids. This coin seats upon the operating-lever, as hereinbefore explained, and the lever is then thrown by the purchaser. This releases the lid, which immediately opens, and the contained package or other article to be vended is slightly raised, whereby it can be conveniently grasped and withdrawn by the purchaser. The lid remains open; for even should the purchaser close it it will not be locked, but will fly back into open position as soon as pressure is removed from it. At the proper time 30 the proprietor or other authorized person visits the apparatus, extracts the coin, as previously described, reinserts the operating-lever, refills the receptacle, and closes and locks the lid, when the apparatus is again ready for 35 vending purposes.

I am aware that many minor changes in the construction, arrangement, and combination of the several parts of this device can be made and substituted for those herein shown 40 and described without in the least departing from the nature and principle of my invention.

Having thus described my invention, what I claim as new, and desire to secure by Letters 45 Patent of the United States, is—

1. In an apparatus of the character indicated, the combination with a locking mechanism including a latch, and a pivoted locking-dog normally holding said latch in locking position, of an operating-lever having a cam-surface adapted to engage the under surface of said dog when said lever is operated and to thus cause said dog to ride upon said cam and thereby throw the dog into inoperative 55 position with relation to said latch; substantially as described.

2. In an apparatus of the character indicated, the combination with a locking mechanism including a latch and a locking-dog, said dog normally holding the latch in locking position, of an operating-lever operating in the plane of one of said members of said locking mechanism, and means for supporting a deposited coin intermediate said lever 60 and the said member not in the plane of said lever, whereby, when said lever is actuated, it operates directly upon the member of the

locking mechanism lying in its path, and, through the medium of the coin, upon the other member of said locking mechanism; substantially as described.

3. In an apparatus of the character indicated, the combination with a locking mechanism including a latch and a locking-dog, said dog normally holding the latch in locking position, of an operating-lever operating in the plane of one of the said members of said locking mechanism, and means on said lever for carrying a deposited coin, whereby, when said lever is actuated, it operates directly upon the member of the locking mechanism lying in its path, and, through the medium of the coin, upon the other member of said locking mechanism; substantially as described.

4. In an apparatus of the character indicated, the combination with a locking mechanism including a latch, and a locking-dog normally holding said latch in locking position, said latch and locking-dog lying in different planes, of an operating-lever lying in the plane of one of said latch members and having provision for carrying a deposited coin in the plane of the other of said latch members, whereby, when a coin is deposited, movement 95 of said lever serves to operate both said latch and said dog; substantially as described.

5. In an apparatus of the character indicated having a supporting-plate, the combination with a locking mechanism including a latch movably supported upon said plate, and a locking-dog for said latch movably supported upon said plate, said latch lying between said plate and said dog, of an operating-lever in the plane of said dog and provided with means for engaging and throwing said dog into inoperative position, and means upon said lever for carrying a deposited coin in the plane of said latch, whereby, in the movement of said lever, said latch is engaged 100 and operated by said coin; substantially as described.

6. In an apparatus of the character indicated, the combination with a locking mechanism including a latch having a notch there- 115 in whereby a shoulder is produced, and a dog which in its normal position lies in the path of the shoulder and locks the latch in a closed position, of means for moving the dog past the shoulder into a position in line with said notch, and opening the latch; substantially as described.

7. In a coin-controlled mechanism or the like, a plate, an operating-lever, and flanges upon said lever and between said lever and plate, and having provision to wholly support a deposited coin, said flanges also serving to space said lever from said plate, whereby a coin-raceway is produced; substantially as described.

8. In a coin-controlled mechanism or the like, an operating-lever adapted to be withdrawn from the apparatus, means for locking said lever in normal, operative position

and for unlocking the same to permit its said withdrawal, and means upon said lever for engaging a deposited coin, whereby said coin is withdrawn with said lever; substantially as described.

9. In an apparatus of the character indicated, a casing having a pivot member, an operating-lever having a coöperating pivot member, said lever being adapted to be withdrawn from said casing, and said pivot members being in separable engagement with each other to permit said withdrawal, and means for locking said lever in the casing with said pivot members in operative engagement and for unlocking said lever to permit its said withdrawal; substantially as described.

10. In an apparatus of the character indicated, a casing provided with a pivot-pin, an operating-lever adapted to be withdrawn from said casing and having a notch adapted to receive said pin when said lever is inserted into said casing, and means for locking said lever in normal, operative position and for unlocking the same to permit its said withdrawal; substantially as described.

11. In an apparatus of the character indicated, an operating-lever adapted to be withdrawn therefrom, and a latch engaging said lever and locking the same in normal operative position; substantially as described.

12. In an apparatus of the character indicated, an operating-lever adapted to be withdrawn therefrom, and a latch loosely entering an opening in said lever, whereby said lever is locked in normal, operative position but is allowed movement upon its pivot; substantially as described.

13. In an apparatus of the character indicated, a plate covering the operating parts, an operating-lever, and a latch therefor, said plate having a slot therein through which access can be had to said latch for operating the same; substantially as described.

14. In an apparatus of the character indi-

cated and having a part adapted to be locked, a latch for locking said part, and means for throwing said latch into unlocking position, said casing having an opening therein through which access can be had to said latch for throwing the same into locking position; substantially as described.

15. In a coin-controlled mechanism or the like, an operating-lever, means whereby said lever is adapted to carry a deposited coin in position for operating the mechanism, and means upon said lever for supporting a coin of smaller diameter than that designed to operate said mechanism and in a position beyond the seat for said proper coin; substantially as described.

16. In a coin-controlled mechanism or the like, an operating-lever having seat members thereon adapted to form a seat for a proper deposited coin but to pass between them a coin of smaller diameter than that of said proper coin, and a seat upon said lever for said smaller coin, whereby said smaller coin is supported upon said lever but does not interfere with the seating of a proper coin; substantially as described.

17. In a coin-controlled mechanism or the like, an operating-lever having front and rear flanges thereon adapted to form a seat for a proper deposited coin but to pass between them a coin of smaller diameter than that of said proper coin; and a seat upon said lever for said smaller coin, whereby said smaller coin is supported upon said lever but does not interfere with the seating of a proper coin; substantially as described.

In testimony whereof I hereunto affix my signature, in the presence of two witnesses, this 27th day of July, 1901.

HARRY J. SHALLER.
